US00D828828S

(12) **United States Design Patent** (10) Patent No.: **US D828,828 S**
(45) Date of Patent: ** *Sep. 18, 2018

(54) **ELECTRONIC DEVICE**

(71) Applicant: **Samsung Electronics Co., Ltd.**, Suwon-si (KR)
(72) Inventors: **Sungkwon Kim**, Seoul (KR); **Kwanue Hong**, Yongin-si (KR); **Chungha Kim**, Seoul (KR); **Giha Woo**, Seoul (KR)
(73) Assignee: **Samsung Electronics Co., Ltd.**, Suwon-si (KR)

(*) Notice: This patent is subject to a terminal disclaimer.

(**) Term: **15 Years**

(21) Appl. No.: **29/559,965**

(22) Filed: **Apr. 1, 2016**

CLAIM

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict environmental subject matter and form no part of the claimed design.

1 Claim, 5 Drawing Sheets
